M. BUCH.
TOP FOR VEHICLES AND THE LIKE.
APPLICATION FILED DEC. 22, 1917.

1,290,070.

Patented Jan. 7, 1919.

Inventor:

Max Buch,

by Special Mission Donaldson Pease,
Atty's.

UNITED STATES PATENT OFFICE.

MAX BUCH, OF DETROIT, MICHIGAN, ASSIGNEE TO HENRY E. EDWARDS, OF JACKSON, MICHIGAN.

TOP FOR VEHICLES AND THE LIKE.

1,290,070.

Specification of Letters Patent.

Patented Jan. 7, 1919.

Application filed December 22, 1917. Serial No. 208,478.

To all whom it may concern:

Be it known that I, MAX BUCH, a subject of the Emperor of Germany, and resident of Detroit, Michigan, have invented certain new and useful Improvements in Tops for Vehicles and the like, of which the following is a specification.

My present invention relates to improvements in tops for motor vehicles and is designed more especially for use in connection with all metal bow constructions.

The invention aims to provide means for securing the top covering material to the bows which will avoid the necessity of using wood fillers and the tacking of the material thereto.

The invention further aims to provide means by which the covering material may be left loose at both ends, so that it can be pulled over the bows to proper position, and tension and thereafter clamped firmly in place.

A still further object is to provide a fastening means which may be readily operated to release the covering when a new top is required, and as readily operated to clamp the new covering material in place.

Other objects will also appear in the following specification.

30 The invention includes the novel features of construction and arrangement and combination of parts hereinafter described, several embodiments of my invention being illustrated in the accompanying drawing in 35 which:

Figure 1 is a fragmentary sectional elevation of a top embodying one form of my invention.

Fig. 1^a is a detail view of a slight modification.

Figs. 2, 3, and 4 are views of further modifications.

Referring by reference characters to this drawing the numeral 1 designates the rear bow of a motor vehicle top; 2 the outrigger bow, and 3, 3, the intermediate bows. As these latter and the manner in which they support the top covering form no part of the present invention they are shown in a 50 conventional manner only.

The bows 1 and 2 constitute terminal bows, to which the front and rear ends of the top covering are secured and they are preferably made of metal tubing of substantially D-shape in cross section with the

flat side on the inside of the bow. The top covering material is indicated at 4 and in my preferred embodiment of the invention it is lapped, or drawn around, the curved outer surface of the bow, and caused to lie 60 against the flat face of the bow to which it is clamped. By thus causing the material to overlap or extend around the curved surface of the tube an extended friction bearing is secured, so that a minimum amount 65 of strain is placed on the clamping or fastening device, and the greater the strain on the covering the greater this frictional engagement. A form of means which I have found desirable for clamping the edge of 70 the covering material is to provide a plurality of threaded studs or bolts 5 projecting from the flat face 2^a of the bow, the covering material being provided with elongated slots to secure these studs and permit the 75 drawing taut of the top material, and a clamping bar 6 forced against the material 4 by the nuts 5^a on the bolts or studs 5. The slots in the covering may be made by a knife or punch while the covering material is being pulled around and against the ends of the bolts.

The projecting edge 4^a of the covering material may be used to connect the edge of what is known in the trade as a valance 85 pocket for carrying the side curtains and thus avoids the necessity of trimming off any of the free edges of the covering material, and also protects said free edge from view. The valance pocket, indicated at 7, 90 may be connected by detachable fasteners of any suitable type, such as snap fasteners indicated at 7^a.

If desired the valance pocket may be connected by carrying its edge between the 95 clamping bar 6 and the top material, as indicated at 7^b, Fig. 1^a.

The clamping strip of the rear terminal bow may also be used to attach the upper end of the rear curtain 8 by simply causing said upper edge to overlie the covering material and be clamped simultaneously therewith to the bow, as indicated at 8^a. This arrangement enables the rear curtain to be readily removed when it is necessary to repair the 100 same or replace the lights.

If desired the clamping bar or member may be secured against the side portion of the bow in the position indicated in Fig. 2, at 6^a. 110

In Fig. 3 I have disclosed forms of terminal bows 1^a and 2^a having recesses 1^x and 2^x in their outer faces into which the covering material is clamped by a flexible wire or metal strip 6^x, the ends of which may be secured to the bows in any suitable manner, as by means of the screws or bolts 9.

In this form the rear curtain may be held by the same clamping wire or strip as indicated at 8^x.

If desired the wire 6^x on the front bow could be sewn in to the curtain valance 2^x, and then clamped over the covering material 4^x, as shown in Fig. 4, and the covering material could be left sufficiently long enough so that the trimmer could get hold of it for pulling it tight. After the wire is pulled tight this curtain valance could be swung upward and fastened against the bow, thereby hiding the edge of the covering material.

For the purpose of tightening the wire, a bolt 9^x could be arranged to pass through the side of the bow having a hole through its head which would lie on the outside for the wire to pass through. The bolt could then be turned around, winding the wire around it until it is tight, and the bolt then could be locked by means of a nut screwed tight on the inside.

What I claim is:

1. In a vehicle top the combination with a bow, of a top covering having its edge lapped around the outer surface of said bow and

provided with elongated slots disposed transversely of the bow, a clamping bar for clamping said covering to the bow by frictional contact, and adjustable means connecting said clamping bar and bow through said elongated slots. 35

2. In a vehicle top, the combination with a bow, of top covering material lapped around the outer face of said bow, means for clamping said material to the inner face of the bow, the edge of the material projecting beyond said clamping device, and a curtain pocket secured to said extended edge. 40 45

3. In a vehicle top the combination with the front and rear terminal bows, of covering material extending between said bows, and adjustable clamping means carried by said terminal bows between which means and the bows the covering material extends, said means being capable of being loosened to allow the covering material to be positioned or tightened from either end and being capable of being operated to clamp said covering material in its adjusted position. 50 55

4. In a vehicle top a terminal bow, covering material lapped around said bow, a clamping bar, means adjustably holding said clamping bar for clamping a part of said lapped portion to said bow on the inside thereof, and a flexible member having an edge clamped between said bar and said part of the lapped portion. 60 65

In testimony whereof, I affix my signature.

MAX BUCH.
